STEPHEN F. BRIGGS AND EDWARD N. JACOBI, OF MILWAUKEE, WISCONSIN,
ASSIGNORS TO BRIGGS & STRATTON COMPANY, OF MILWAUKEE, WISCONSIN, A CORPORATION OF WISCONSIN.

POLARITY-REVERSING SWITCH.

1,408,687.

Specification of Letters Patent. Patented Mar. 7, 1922.

Application filed February 10, 1917. Serial No. 147,914.

To all whom it may concern:

Be it known that we, STEPHEN F. BRIGGS and EDWARD N. JACOBI, citizens of the United States, and residents of Milwaukee, in the county of Milwaukee and State of Wisconsin, have invented new and useful Improvements in Polarity-Reversing Switches, of which the following is a description, reference being had to the accompanying drawings, which are a part of this specification.

This invention has for its object to provide a polarity reversing switch of the rotary type, controlled by a key so as to be locked when the key is removed, and therefore suitable for controlling the ignition circuit of automobile gas engines in order that unauthorized use of the automobile may be prevented and in order that the direction of current flow through the ignition apparatus may be reversed with successive operations of the switch to minimize pitting of contacts by which the battery circuit is frequently made and broken during the operation of the engine.

Another object of the invention is to produce such a switch with lock mechanism that will be practically incapable of operation in the absence of the proper key to prevent theft of the automobile.

Another object of the invention is to produce a polarity reversing switch of the rotary type with a ratchet controlled switch member and all parts compactly arranged to produce a strong and durable switch structure inexpensive to manufacture.

With the above and other objects in view the invention consists in the polarity reversing switch as herein claimed and all equivalents.

Referring to the accompanying drawings, in which like characters of reference indicate the same parts in different views:

Fig. 1 is a front view of a polarity switch constructed in accordance with this invention;

Fig. 2 is a rear view thereof;

Fig. 3 is a rear view of the front plate with the base or terminal head removed;

Fig. 4 is a similar view with the switch member also removed;

Fig. 5 is a top view of the switch base or terminal head, a position of the contact springs in an "off" position of the switch being shown in dotted lines;

Fig. 6 is a central sectional view; 5

Fig. 7 is a sectional view of the device through two of the terminal bushings connected by one of the contact springs;

Fig. 8 is a top view of the switch member;

Fig. 9 is a perspective view of the key 6 guide;

Fig. 10 is a detailed sectional view showing the mounting of the key guide;

Fig. 11 is a central sectional view of a modified form of the switch in which a multiple tumbler lock is incorporated therein;

Fig. 12 is a bottom view thereof with parts sectioned and showing the position of the lock tumblers when the key is withdrawn;

Fig. 13 is a further sectional view showing the engagement of the lock tumblers with the arms of the lock crab; and,

Fig. 14 is a perspective view of the lock crab.

In these drawings 15 indicates a front plate provided with a central opening surrounded by a bead containing four equally spaced notches forming key slots 16 at right angles to each other. Secured to the back of 80 the front plate, as by means of rivets 17, is a cup-shaped switch case 18 with its top forming a downwardly extending annular flange, 19 around the central opening of the front plate.

A key guide, 20, consisting of a strip of sheet metal cut and formed as shown in Fig. 9, has its oppositely directed semi-circular top flanges 21 fitting within the annular flange 19 and bearing against the bead of 90 the front plate. The lower end of this U-shaped key guide has its opposite shoulders cut away so that the central portion forms an arch-like projection 22 which bears within the round central portion of a cross-shaped opening 23 at the center of a funnel-shaped switch member 24. This switch member 24 consists of a flanged metal cup with diametrically opposite arc-shaped blocks of insulating material 25 riveted to 100 its flange. Notches 26 are cut in the flange of the switch member to form regularly spaced shoulders to engage inclined ratchet teeth 27 formed by tongues cut from the top of the switch case 18. These shoulders of the switch member are held in engagement with the inclined tongues or ratchet teeth 27 by the spring action of arched or bowed con-

tact springs 28 which are riveted to the insulating blocks 25 and have their downwardly bent ends terminating in spherically convexed switch contacts bearing against an insulating block 29 secured within the casing by screws 30. The insulating block 29 forms a terminal head with terminal bushings 31 passing therethrough and forming equidistant contacts engaged by the convexed ends of the contact springs 28. The four terminal bushings have screws threaded in them with washers forming binding posts 32, two diametrically opposite binding posts being intended for connection with the terminals of the battery while the others are connected with the terminals of the ignition system.

The terminal head 29 has a central recess 33 into which the cylindrical lower end of the cup-shaped switch member 24 projects to obtain a guide bearing. A flat key 34 is adapted to be inserted through one key slot 16 or the other according to the position of the key guide and then passes between the parallel side walls of the key guide which have spring tongues 35 cut therefrom to bear with pressure against opposite faces of the key and the two horns 36 at the end of the key straddle the stirrup or contracted bent portion 22 of the key guide and enter the cross-shaped opening 23 of the switch member 24. In the fully inserted position of the key, determined by its end between the horns 36 engaging the bent portion of the key guide, opposite notches 37 therein register with the head of the front plate so that the key may be turned and in so doing rotate the switch member to carry each spring contact across the surface of the insulating terminal head from one terminal bushing to the next or to positions between terminal bushings. These positions for the contacts are determined by the ratchet teeth 27 which compel the switch member to be turned progressively in the same direction and thus necessitate the change in polarity of the circuit connections with each succeeding closing of such connections. The contact springs 28 in one closed position of the switch connect a battery terminal bushing with an ignition circuit terminal bushing on one side thereof while in the next closed position they connect said battery terminal bushing with the ignition circuit terminal bushing on the other side thereof, thus reversing the direction of current through the ignition circuit. Having moved the switch member from an "on" position to an "off" position by the turning of the key a distance indicated on the front plate by appropriate markings thereon it is impossible to turn the key back so as to reestablish the circuit with the same direction of current flow on account of the action of the ratchet, and the key will only register with the key slots 16 in the front

plate when the switch is in an "off" position and consequently its removal is prevented whenever the switch is in position to close the circuit. With the ignition switch in the "off" position and the key removed theft of the automobile is prevented through the inability of the engine to operate with its ignition circuit open and the switch may not be closed by means other than the key, such for instance as a screw driver, for the engaging notches of the cross-shaped opening 23 in the switch member 24 are inaccessible except through the openings on opposite sides of the bent portion 22 of the key guide 20. The cross-shaped key openings also prevent such false operation of the switch.

The switch member is rotatably held in place by the terminal head and the spring action of the contact springs serves to hold it against the top of the case to cooperate with the ratchet teeth.

A modification of the invention in which the switch is positively locked against false operation by means of a multiple tumbler lock mechanism is shown in Figs. 11 to 14, inclusive, wherein, in place of the key guide 20, the cylindrical portion of the switch member 24 has secured within it by means of screws 38 a cylindrical lock barrel 39 with a sinuous key passageway therethrough to receive a corrugated key 40. This lock barrel is crossed transversely by a number of tumbler plates 41 having openings through which the irregular edges of the key fit and said tumblers are adapted to project from the barrel when the key is removed. Instead of the annular flange 19 the edge of the lock case around its central opening has riveted thereto the outwardly bent ends of the four upstanding arms of a skeleton lock frame 42, as shown in Fig. 14, the lower ring portion of which fits around the lock barrel 39. When the key is removed the sliding tumblers 41 are adapted to project from the lock barrel 39 and fit between the parallel arms of the stationary lock frame 42, as shown in Fig. 12, so that the lock barrel can only be turned when all the tumblers are withdrawn therein by the use of a key having edges of the proper contour to correspond with the irregular positioning of the openings of the sliding tumblers as shown in Fig. 11. The other features of the switch structure correspond with the form of the invention first described.

What we claim as new and desire to secure by Letters Patent is:

1. A ratchet switch, comprising a casing having ratchet teeth, a rotary switch member within the casing, ratchet teeth on one face thereof to cooperate with the ratchet teeth of the switch casing to permit the switch member to turn only in one direction, contact springs on the other face of the switch member, and a terminal head in the

switch casing having contacts engaged by the contact springs, said contact spring serving to give pressure to the switch member to effect the engagement of the ratchet teeth.

5 2. A ratchet switch, comprising a switch case having ratchet teeth, a switch member therein also having ratchet teeth, a terminal head fitting in the switch case and provided with switch contacts, and spring arms carried by the switch member and bearing on the terminal head to force the ratchet teeth into engagement and adapted to contact with the switch contacts.

15 3. A pole reversing switch, comprising a switch case provided with ratchet teeth, a rotary switch member within the switch case provided with cooperating ratchet teeth, a terminal head on the switch casing, means for giving pressure to the switch member for 20 forcing the ratchet teeth into engagement comprising spring contacts on the switch member bearing on the terminal head, and switch contacts on the terminal head engaged by the spring contacts in different 25 ratchet determined positions of the switch member for effecting different circuit connections.

4. A pole reversing switch, comprising a switch case provided with ratchet teeth, a 20 rotary member therein provided with cooperating ratchet teeth, a terminal head in the switch case, switch contacts thereon, and bowed contact springs on the switch member engaging the terminal head and giving pressure to the switch member for holding the 35 ratchet teeth in engagement, said bowed contact springs engaging and connecting different pairs of switch contacts in different positions of the switch member.

40 5. A switch, comprising a switch case, a terminal head secured thereto and provided with a central opening and with switch contacts, a switch member having a central cy-

lindrical portion fitting within the recess of the terminal head, contact springs carried by the switch member and bearing on the terminal head for engaging the switch contacts thereof, a cylindrical lock barrel secured to the cylindrical portion of the switch member and passing through the switch case, a lock frame secured to the switch case and surrounding the lock barrel and having arms with spaces therebetween, tumblers in the lock barrel projecting between the arms of the lock frame, and a key fitting in the lock barrel and engaging the sliding tumblers for withdrawing them from between the arms of the lock frame to permit the switch member to be turned by means of the key.

6. A switch, comprising a switch case, a terminal head secured thereto and provided with a central opening and switch contacts, a switch member having a central cylindrical portion fitting within the recess of the terminal head, contact springs carried by the switch member and bearing on the terminal head to engage the switch contacts, a lock member within the cylindrical portion of the switch member and a cylindrical skeleton lock frame surrounding the lock member with upwardly extending spaced arms riveted to the end of the switch case adapted to have the lock member engage the arms thereof, and a key for the lock member for removing it from engagement with the arms of the lock frame and for turning the switch member.

In testimony whereof, we affix our signatures, in presence of two witnesses.

STEPHEN F. BRIGGS.
EDWARD N. JACOBI.
